CLOSURE CAP LOCK

Kyle E. Stant, Connersville, Ind.

Application October 18, 1932, Serial No. 638,356

6 Claims. (Cl. 220—24)

This invention relates to improvements for closure caps for containers such as automobile fuel tanks, radiators or the like. More specifically it relates to closures of the hinged or lid type in which the base or collar portion thereof must be fastened permanently and securely to the container.

The main object of the invention is the provision of a device of the class described which may be easily, quickly and permanently attached to the filler opening of a container without the use of special tools or any great amount of mechanical knowledge, and a means thereon to prevent unauthorized removal of the cap from the filler opening.

Another important object is the provision of such a device in which is contained suitable means as will allow adjustment of the cap axially of the filler opening so as to allow the hinged lid to open in a convenient direction.

These, as well as other objects, will become more apparent upon consideration of the drawing and description specifically related thereto.

Referring to the drawing:

Fig. 1 is a vertical sectional view of the device taken on line 1—1 of Fig. 3.

Fig. 2 is a vertical sectional view taken on line 2—2 of Fig. 4.

Fig. 3 is a bottom plan view of the device before being turned into clamping position.

Fig. 4 is a bottom plan view of the device in clamped position and with the key member in locking position.

Fig. 5 is a perspective view of the clamp ring showing the clamp hooks and key.

Fig. 6 is a perspective view of the filler spout showing cams, stops, and entrance openings.

Fig. 7 is a fragmental perspective view of the collar.

In the present embodiment of the invention, the drawing shows a portion of the filler neck 8, having thereon flanged portions 9 and 10. Depending from the flanges 9 and 10 are the cam and stop members 11 and 12, and cut through the flanges 9 and 10 are the entrance openings 13 and 14. The collar is designated by the numeral 15 and the cover for the collar is numbered 16. This cover is not a part of this invention as any suitable cover may be used. Located around the inside diameter of collar 15 is a shoulder 17. This shoulder performs a dual purpose; first, it is adapted to press the gasket 18 against the end of the filler tube 8; and second, it carries upon its upper surface the ring 19.

Carried on the shoulder 17 is the rivet 20 which

fits holes 21, 22 and 23 in the ring 19, there being three holes in the present embodiment which allow three different positions of the base and lid rotatively of the spout. It is obvious that there may be a greater or lesser number of holes as preferred. Depending from the ring 19 are the rigid hook members 24 and 25 which are adapted to operate on cams 11—11 and stops 12—12. These hooks are herein shown and considered as being formed integral with the ring 19, but need not necessarily be constructed in such manner, as they may be formed separately and fastened in any solid and rigid manner to the ring member. Also, carried on the ring 19 and depending therefrom is the resilient or yielding member 26. This member may be made either of a soft yielding material which may be bent into the desired position manually, or it may be made of a spring-like or resilient material which will assume the desired position automatically. The operation of the member 26 will be explained more in detail hereinafter.

The novel features of this device will be better understood by a description of the operation of installing it on a filler spout.

Installation is accomplished by placing the hooks 24 and 25 down through the filler spout entrance openings 13 and 14, and turning the collar until the hooks strike the stops 12—12 as is clearly shown in Fig. 4. When the collar is placed on the filler spout with the hooks through the entrance openings, the member 26 is in a position along side one of the cams 11. If the member 26 is of a resilient nature, it will be pressing against the side of the cam, but if it is made of a yielding or manually bendable material, it simply depends along the side of the cam but does not press thereagainst.

If the member 26 is resilient it will ride against the side of the cam 11 when the collar is turned until it reaches the opening 13 or 14, then, because of its resilient nature, it will spring outward into this opening and therefore back of the stop 12. When the member 26 is in the opening 13 or 14 it prevents reverse rotation of the collar to remove it from the filler spout.

If the member 26 is not resilient but is of a soft or yielding nature, it accomplishes the same purpose. It is rotated by the collar to a position directly in front of the opening 13 or 14 and is then bent manually into the opening and back of the stop 12. In both the case of the resilient member 26 and the soft or yielding member 26, the said member is located on the ring in a pre-determined, spaced relationship to the hooks 24

and 25 so that it may pass entirely into the opening 13 or 14 before the hooks strike the stops 12.

Removal of the device from the filler spout is accomplished by simply grasping the key member by its lower end or prying thereon with a suitable tool so that the said key member is moved out of the entrance opening, then rotating the collar anti-clockwise until the hooks may be lifted up through the entrance openings of the spout.

The gasket 18 may be of any suitable material which is of a compressible or resilient nature. Cork or rubber are the most common materials which could be used for this purpose. The hooks 24 and 25 are of such shape and are so spaced from the shoulder 17 on the collar, that when the collar is rotated on the filler spout, they coat with the cams on the spout to compress the gasket 18 between the filler spout and the shoulder 17, thus sealing the collar to the spout.

While I have shown the preferred form of my invention as known to me it will be understood that various changes in the combination, construction, and arrangement of the parts may be made by those skilled in the art without departing from the spirit of the invention as claimed.

Having thus described my invention, what I claim and desire to secure by Letters Patent is:

1. In a closure for a receptacle, in combination, a tubular filler extension on the receptacle having cams and entrance slots thereon, a collar adapted to be supported by said filler extension, rigid clamping means permanently attached to the collar adapted to cooperate with said cams for clamping said collar to said filler extension, and a yielding member attached to said collar adapted to be moved into an entrance slot on said filler extension during clamped engagement of said collar with said filler extension.

2. In a closure for a receptacle, in combination, a filler spout on the receptacle having cams, stops and entrance openings thereon, a collar adjacent the open end of the spout, inherently rigid locking members fastened immovably to the collar, said locking members adapted on rotation of the collar on the spout to coat with the cams and stops to clamp the collar to the spout, a resilient key member one end of which is fastened immovably to the collar and the other end depending therefrom, said resilient key member adapted to press resiliently against the cams, whereby when the collar is rotated into locked position said resilient key member will coat with the cams and when the collar is in locked posi-

tion will move by its own resiliency to a position in an entrance slot of the spout, whereby further rotation of the collar relative to the spout is limited.

3. In a closure for a receptacle, in combination, a filler spout on the receptacle, a collar rotatably mounted on the filler spout, cooperating rigid locking members on the collar and the spout for clamping the collar and spout together upon rotation of said collar, a notch between the locking members on said spout, and manually movable key means on the collar adapted to be moved into said notch during clamped engagement of said collar to said filler spout, whereby rotation of the collar on the spout is limited.

4. In a closure for a receptacle, in combination, a filler spout on the receptacle, a collar mounted rotatably on said filler spout, cooperating rigid locking members on the collar and the spout for clamping said collar and spout together upon rotation of said collar, a notch between the locking members on said spout, a resilient key on the collar adapted to automatically snap into said notch during rotation of said collar to limit rotation of said collar on the spout.

5. In a closure cap for a receptacle, in combination, a spout having a flange with entrance slots therein, a collar adapted to be carried by said spout, a separate ring carried by said collar and having a pair of rigid hooks depending therefrom, a yielding member depending from said ring adjacent one of said hooks, a connecting means associated with the collar and the ring adapted to limit relative rotation therebetween, said yielding member adapted to be moved into an entrance slot when said hooks are positioned beneath said flanges, whereby the collar is both clamped to the spout and rotational movement thereof limited relative to the spout.

6. In a closure for receptacles, in combination, a bayonet filler tube having a slot and projecting member thereon, a collar adapted to be supported by said filler tube, means associated with said collar for clamping engagement with said projecting member to prevent vertical displacement of said collar relative to said filler tube, a depending yielding member fixedly carried by said collar, the lower portion of said yielding member being adapted for movement into said slot on said filler tube during the clamped engagement of said collar with said filler tube, whereby rotation of said collar relative to said filler tube is limited.
